KEY CASE

Filed July 12, 1926

Inventor:

Howard Fischer

UNITED STATES PATENT OFFICE

HOWARD L. FISCHER, OF ST. PAUL, MINNESOTA

KEY CASE

Application filed July 12, 1926. Serial No. 121,864.

My invention relates to key cases wherein it is designed to provide a key case of a simple, inexpensive nature, yet having the functions and utilities most desirable in an article of this nature.

A feature of the invention resides in a key case designed to be entirely flexible so that the case will be pliable in the user's pocket, having no stiff or hard supporting members 10 for the keys such as a bar extending across the key case to support the key hooks.

It is also an object of my invention to provide a key case made of flexible material such as leather or other suitable similar material 15 which is folded over the keys and adapted to incase the same so that the case can be carried in the pocket without wearing on the same.

My key case is designed of two principal parts which are adapted to be secured together by a series of eyelets. These eyelets 20 form an attachment for the individual key hooks. These eyelets are adapted to be spaced apart and thus form a flexible edge to which the key hooks are attached so that the 25 key case may readily flex in use, yet having the necessary rigidity to support the key hooks from the edge.

The simplicity of my key case is an important feature of my invention. No sewing is 30 required, and by means of a series of eyelets, the members are fastened together while a snap catch is adapted to hold the flaps of the key case closed over the keys in the case.

It is also a feature of my invention to provide a flexible key case made of two parts of leather or other flexible material, held together by a series of eyelets, which eyelets, with the flexible case, form a pliable and flexible attaching part for the key hooks and the 40 key hooks are supported sufficiently free to turn into or out of the key case together with sufficient freedom to permit partial rotation of the keys, practically obviating the necessity of a swivel joint for attaching the key 45 hooks to the case.

It is obvious, however, that a swivel joint can be employed, if desired, to support the key hooks so that a full rotation of the keys can be secured, if desired. Where only the 50 key hooks are used with the eyelets extend-

ing through the case, a very simple construction having an economical nature is provided which gives the flexibility to the case so that no rigid or stiff key hook supporting members are employed which have been found to 55 be objectionable in key cases where they are carried in the pocket.

These features, together with other details of my invention will be more clearly and fully set forth in the specification and claims. 60

In the drawings forming part of this specification:

Figure 1 is a front view of my key case in open position showing keys attached to the key hooks, some of the key hooks being turned 65 out of the case.

Figure 2 illustrates a back view of my key case showing one key and supporting hook turned out of the case while the case flaps are 70 in closed position.

Figure 3 is a geometrical development of the body of my key case as it would appear stamped out from a piece of leather or other suitable material.

Figure 4 is a geometrical development of 75 the inner member of my key case as it would appear stamped from leather.

Figure 5 is a longitudinal section through my key case showing the position of the key hooks in relation to the securing eyelet. 80

Figure 6 is a section through a portion of the key case illustrating the key hook attached by a swivel connection.

In the drawings my key case A is formed with a body portion 10 made of leather or other suitable flexible material which is stamped out in formation, illustrated in Figure 3 extending from the body 10 of the key case to the flat members 11 and 12.

My key case A may be provided with an inner member 13 adapted to fit into and extend across the body portion 10 which is adapted to be secured to the body portion by the eyelets 14. These eyelets 14 form a very desirable and suitable reinforcing attachment for 90 the key hooks 15. The eyelets are adapted to extend through the openings 16 and 17 formed in the body 10 of the case A and in the member 13, respectively. 95

A suitable snap fastener having one por- 100

tion 18 attached to the flap 11 and the other portion 19 attached to flap 12 is provided to lock the flaps 11 and 12 overlapping each other to close the key case.

5 By this extremely simple construction, I provide a key case adapted to carry a series of keys such as B on the hooks 15 while the eyelets 14 form a flexible and pliable attachment for the hooks 15 yet forming a reinforced portion so that the key case will stand 10 considerable wear without appreciably affecting the key case even though it goes through very hard use.

15 My key case is to be desired over the other constructions because of its flexibility through the eyelet attaching means for the key hooks.

Thus, when my key case is carried in one's pocket, its pliable nature will not make it objectionable.

20 In Figure 6, I have illustrated a swivel connection for the key hooks 15 which is carried by the ring 21 extending through the eyelets 14.

25 It is practically not necessary to use a swivel connection for my key hooks 15, because the key hooks extend freely through the eyelets 14 and sufficient freedom is provided to permit the keys to turn sufficiently to practically obviate the necessity of having 30 a swivel, although a swivel can be used, if desired.

It will be noted that my key case is formed 35 of a very simple, economical nature having only two parts, one of which may be eliminated, if it is desired, this part being the inner member 13, and my key case will operate equally well with the series of eyelets 14 for supporting the key hooks to the body 10 of the case A.

40 In accordance with the patent statutes, I have described the principles of operation and construction of my invention and while I have illustrated in the drawings a form of carrying out the same, I desire to have it understood that the drawings are only illustrative, and that the invention can be carried out within the scope of the following claims.

I claim:

50 1. A key case including a cover member with closing flaps, a member adapted to be positioned in said cover member, eyelet members for attaching said second member in said cover member and key hooks adapted to extend through and being supported by said 55 eyelet members.

55 2. A key case formed of two flexible parts, one of said parts constituting a cover with closing flaps, the other part adapted to be positioned in said cover, a series of eyelets 60 for attaching said second mentioned part in said cover, providing a flexible key supporting means and key supporting hooks adapted to be supported by said eyelets.

65 3. A key case comprising a cover member, an inner member positioned in said cover

member, a series of eyelets for attaching said cover member and inner member together along one edge of said case and a series of key attaching members carried by said eyelets.

70 HOWARD L. FISCHER.
